(57) **CLAIM**

The ornamental design for an arm and reclining chair as shown and described.

DESCRIPTION

FIG. 1 is a front view of an arm and reclining chair.

FIG. 2 is a top view thereof.

FIG. 3 is a left side view thereof.

FIG. 4 is a right front perspective view thereof; and, FIG. 5 is a left rear perspective view thereof.

The bottom view is not illustrated in the drawings, as the bottom view is not visible to an ordinary observer of the arm and reclining chair and forms no part of the claimed design.
